CLIP FOR SPECTACLE CASES

Philip C. Scott, Kemptown, Ill.

Application December 2, 1939, Serial No. 307,321

1 Claim. (Cl. 24—3)

This invention relates to clips or clasps and more particularly to a clip or clasp particularly designed for use on a spectacle case, or cases for pencils, pens, and similar articles, and as are commonly carried in the breast pocket of garments.

An object of the present invention is to provide a clip or clasp of this character which is extremely simple in construction and at the same time is well-adapted for the purpose intended.

The invention together with its objects and advantages will be best understood from a study of the following description taken in connection with the accompanying drawing wherein:

15 Figure 1 is an elevational view of a spectacle case having the clasp mounted thereon.

Figure 2 is a side edge view thereof with the clasp shown in open position.

20 Figure 3 is a fragmentary top edge view of the case with the clasp thereon, and

Figure 4 is a fragmentary side edge view of the case with the clasp mounted thereon, and with the clasp shown in closed condition and with certain parts thereof broken away and shown in section.

25 Referring more in detail to the drawing it will be seen that in the preferred embodiment thereof the clasp indicated generally by the reference numeral 5 is formed from a single blank of spring metal or other suitable material cut, shaped and dimensioned to provide a combination attaching plate and fixed jaw 6, and a movable complementary jaw 7.

30 In forming the jaws 6 and 7 the plate is bent into a substantial U with the bight 8 acting as a spring tending to yieldably urge the jaw 7 away from the jaw 6.

Also the end portion of the plate from which the clasp is made, and constituting the jaw 7, is laterally reduced for obvious utilitarian and decorative purposes.

35 In mounting the clasp 5 on the case 9, which latter may be, and as shown in the drawing, a spectacle case, the combination fixed jaw and attaching plate 6 of the clasp is disposed against one side wall, preferably the rear flat wall of the case 9 and is riveted or otherwise secured thereto through the medium of fastening elements 10.

40 Also anchored to the combination attaching plate and jaw 6 of the clasp and extending therefrom is a substantially U-shaped member 11 the legs of which are accommodated by apertures 12 provided therefor in the jaw 7 of the clasp.

45 55 Pivottally or rotatably mounted on the member

11 at the closed end of the latter is a locking cam 13 that is provided with a suitable integral finger piece or handle 14.

Also, to increase the effectiveness of the clasp the jaw 7 at the free end or edge thereof is bent 5 inwardly to provide an inwardly directed angular gripping lip or edge 15.

In using the device it will be apparent that when the cam 13 is swung to the position shown in Figure 2, jaw 7 will swing outwardly from the 10 jaw 6 so as to accommodate between the jaws the edge of a pocket of a garment. With the edge so accommodated between the jaws the cam 13, in an obvious manner, is rotated in a clockwise direction thus causing the jaw 7 to move inwardly 15 towards the jaw 6 so that the edge 15 thereof will serve to effectively clamp between said edge 15 and the jaw 6 of the clasp the wall of the garment pocket thereby securing the case within such pocket against casual displacement and 20 possible loss.

Also in accordance with the present invention the clasp 5 is provided at the web or bight 8 thereof with an aperture 4 for accommodating a chain, such as a watch chain or the like, to the 25 end that the fastener may be used, as for example, for securing one end of such chain in the pocket, for example, of a man's vest; or for any other use as may be found desirable in addition to the use of the clasp on spectacle cases, and the 30 like as hereinabove described in detail.

It is thought that a clear understanding of the construction, utility and advantages of a clasp embodying the features of the present invention will be had without a more detailed description 35 thereof.

Having thus described the invention what is claimed as new is:

A clasp of the class described comprising a substantially U-shaped member formed of flat 40 material to provide flat limbs of considerable width, one limb having a pair of holes therein intermediate its ends, a U-shaped member having its limbs passing through said holes with the ends of its limbs fastened in the other limb of the 45 first U-shaped member, a cam having an eccentrically arranged hole therein through which passes the bight of the second U-shaped member, a handle on the cam, said cam when in a certain position engaging the limb of the first member 50 which has the hole therein for pressing said limb toward the other limb of the first member and the bight of the first member having a chain receiving hole therein.
